UNITED STATES PATENT OFFICE

168,237

COMPOSITE LENS FOR RUNWAY LIGHTS

Willis A. Pennow, Cleveland, Ohio, assignor to
 Westinghouse Electric Corporation, a corpora-
 tion of Pennsylvania

Original application December 27, 1950, Serial No.
 13,602. Divided and this application April 18,
 1952, Serial No. 19,380

Term of patent 14 years

(Cl. D43—16)

To all whom it may concern:

Be it known that I, Willis A. Pennow, a citizen of the United States, residing at Cleveland, State of Ohio, have invented a new, original, and ornamental Design for a Composite Lens for Runway Lights, of which the following is a specification, reference being had to the accompanying drawing, forming a part hereof.

Fig. 1 is a side elevational view taken in the direction of the arrows I—I of Fig. 2 of a composite lens for runway lights, showing my new design; and

Fig. 2 is a top plan view thereof.

The dominant features of my new design are shown in the drawing by solid lines.

This application is a division of my copending application Serial No. D-13,602, filed December 27, 1950.

I claim:

The ornamental design for a composite lens for runway lights, as shown and described.

WILLIS A. PENNOW.
